UNITED STATES PATENT OFFICE

2,558,545

HOT-WATER AND STEAM GENERATOR

Frank W. De Luchi, Los Banos, Calif.

Application November 6, 1947, Serial No. 784,482

2 Claims. (Cl. 122—216)

1

This invention relates to fluid heaters.

An object of this invention is to provide a heater of the instantaneous type whereby low pressure steam may be obtained in a continuous flow.

Another object of this invention is to provide a heater of this type which will produce either steam or hot water. Where hot water is desired the inlet valve for supplying water to the heater is opened relatively wide, whereas when only steam is desired the inlet or supply valve is cut down so as to reduce the quantity of water supplied to the heater.

A further object of this invention is to provide a heater which will produce steam after the manner of a flash steam generator, the heater embodied in this invention including a plurality of superposed generators with a cone-shaped baffle extending from each generator for concentrating and directing the rising heating gases toward the center of a succeeding generator.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a vertical section of a heater constructed according to an embodiment of this invention.

Figure 2 is a fragmentary detailed front elevation of the heater.

Figure 3 is a sectional view taken on the line 3—3 of Figure 1.

Referring to the drawing, the numeral 10 designates generally a jacket of insulated construction which is formed of an outer cylindrical shell 11, an inner cylindrical shell or wall 12 and heat insulating means 13 between the two shell members 11 and 12.

The jacket 10 is supported above a plane surface by means of a plurality of supporting feet or legs 14 which are fixed to the lower end of the jacket 10. The jacket 10 has a closure or door 15 hingedly secured as at 16 to the lower portion thereof and the door 15 is adapted to be latched in closed position by means of a latching bolt 17.

The jacket 10 also includes a cap 18 mounted on the upper end of the jacket which is formed with a marginal flange 19 detachably secured to the upper end of the outer shell 11 by fastening

2

means 20. The cap 18 also includes an upwardly projecting nipple 21 for connecting a vent pipe thereto. A burner 22 of the Bunsen type is disposed in the lower portion of the jacket 10 being connected with a pipe 23 which is connected to a source of gas supply. A valve 24 is mounted in the supply pipe 23 at a point closely adjacent the jacket 10. The lower end of the jacket 10 has mounted therein a cylindrical air duct 25 which engages loosely about the burner 22 being open at its lower end upper ends and the duct or sleeve 25 is secured to a plate 26 having a marginal flange 27 secured by fastening means 28 to the lower end of the outer shell 11.

15 In order to provide for the generation of low pressure steam or hot water, I have provided within the jacket 10 a plurality of superposed spaced apart hot water generating or heat exchanging members generally designated as 29. 20 The generating members 29 are connected together by means of nipples 30a and a lower nipple 30 connects the lower generator 29 with a T-coupling 33 carried by a horizontal supply pipe 31. The pipe 31 has a T-coupling 33 connected thereto with the central branch of which the vertical pipe 30 is connected and an extension pipe 31a projects from coupling 33 and has a lower pressure relief valve 32 secured to the outer end thereof. Each generating member 29 includes 25 lower and upper disc shaped plates 34 and 35 which are connected together at their outer edges by a connecting flange 36 thereby forming a steam generating chamber 37. The chamber 37 is relatively thin so that the water discharged 30 into the chamber 37 will be turned into steam by substantially the flash process.

The lower plate 34 has formed integral therewith a boss 38 and the upper plate 35 has formed integral therewith a boss 39. An outlet pipe 40 is connected to the upper nipple 30b by means of a T-coupling 41 and the pipe 40 extends laterally through the jacket 10 at the upper end of the latter and has a relief valve 42 connected therewith. Preferably the outer shell 11 is slotted as 45 indicated at 43 so that the steam generating unit which comprises the series of generating members 29 secured to the pipe 30 may be removed from the jacket as a unit by uncoupling the supply pipe 31 and the lower relief valve 32 with extension 31a and also outlet pipe 40. The jacket 10 also has mounted therein a series of frusto-conical shaped baffles 44 which are mounted one above each generator 29. The base of each baffle 44 has extending thereacross a pair of supporting 50 bars 45 which are welded or otherwise fixedly

secured as indicated at 46 to the top of an adjacent generator as 29. In this manner the base of each baffle 44 will be substantially coplanar with the upper side of each generator and the baffles can be removed as a unit with the generators 29.

In the use and operation of this heater the burner 22 is lighted by turning on the valve 24. When the burner 22 is lighted, the heating gases from this burner rising in the insulated jacket 10 will heat the generators 29 in succession, the heating gases passing over and about each generator and then being confined by the cone-shaped baffles 44 so that the heating gases from a lower generator passing a lower baffle will strike an upper generator adjacent the center thereof. The generators 29 are substantially smaller in diameter than the diameter of the base of the baffles 44 so that the heated air may readily flow about the marginal edges of the generators 29. The heater as hereinbefore described has been designed as a low pressure steam generator for use in dairies or the like where steam or hot water is desired for sterilizing the milk cans or other apparatus found in a dairy.

I claim:

1. An instantaneous heater comprising an insulated housing, a cap on the upper end of said housing, said housing having a slot in the upper end thereof and projecting below said cap, said housing also having an opening diametrically opposite from said slot, a lower supply pipe extending into said housing, an upper horizontal outlet pipe engaging in said slot and projecting from said opening, a plurality of vertically spaced apart disc-shaped hollow generators in said housing, nipples connecting said generators together

and to said supply and outlet pipes, a frusto-conical baffle on the upper side of each generator having the base thereof larger in diameter than the diameter of said generator, a pair of parallel supporting bars fixed at their opposite ends in the lower portion of each baffle and also fixed to the upper side of a generator, and a burner in said housing below the lowermost generator.

2. In a heater having an insulated housing with 10 a plurality of vertically spaced apart disc shaped generators therein and nipples connecting the generators together; a frusto-conical baffle on the upper side of each generator, a pair of parallel bars fixed at the ends thereof to the base 15 of said baffle having the base thereof larger in diameter than the diameter of said generator, and means fixedly securing said bars to said generator.

FRANK W. DE LUCHI.
